UNITED STATES PATENT OFFICE.

WILLIAM T. CROSLIN, OF OKLAHOMA, OKLAHOMA, ASSIGNOR OF ONE-HALF TO JAMES P. WOOLSEY, OF OKLAHOMA, OKLAHOMA.

APPARATUS FOR RAISING WATER.

1,153,198.

Specification of Letters Patent. Patented Sept. 14, 1915.

Application filed June 11, 1914. Serial No. 844,511.

To all whom it may concern:

Be it known that I, WILLIAM T. CROSLIN, a citizen of the United States, residing at Oklahoma city, in the county of Oklahoma and State of Oklahoma, have invented certain new and useful Improvements in Apparatus for Raising Water, of which the following is a specification, reference being had to the accompanying drawings.

10 An object of the invention is to provide improved means for raising water.

Other objects and advantages of the invention will be set forth in the ensuing description.

15 One embodiment of the invention in practical form is shown by the accompanying drawings, in which:

Figure 1 is a sectional view of a well, showing the improved apparatus installed 20 for use. Fig. 2 is a sectional view of a casing and associated parts, which are submerged in the water supply. Fig. 3 is an enlarged elevation view in the same direction as Fig. 1, showing improved mechanism 25 for controlling compressed air. Fig. 4 is an elevation view, on a little larger scale and in the direction of the arrow 4, of parts shown in Fig. 3. Fig. 5 is a sectional view in the same direction as Fig. 4 and taken on 30 the line 5—5 of Fig. 3.

Referring to the several figures, in all of 25 which like characters of reference designate like parts, the improved apparatus includes a casing 6 which is submerged in the water supply and adapted to withstand internal fluid pressure, the lower wall of this casing having one or more openings 7 provided with valves 8. In this instance, the casing 6 is supported by blocks 9 resting on the bottom 10 of the well 11, but it may be supported in any other suitable manner, such, for example, as suspending it by certain pipes which lead to and from it.

A pipe 12 leads from a tank 13 or other 45 source of compressed air into the casing 6, while a second or delivery pipe 14 leads upward from the lower part of said casing and is provided with a valve 15. A third or exhaust pipe 16 leads from the upper part of 50 the casing 6, and is provided at its outer end with a valve 17 whose opening may be adjusted to cause back pressure of air for purposes later shown.

In operation, water first forces the valves 8 open and fills the casing 6, the displaced

air escaping out the exhaust pipe 16. The exhaust pipe 16 is then closed and the inlet pipe opened, placing the contents of the casing 6 under pressure and forcing the water up the delivery pipe 14. When the casing 6 is emptied of water, the exhaust pipe 16 is opened and the inlet pipe 12 closed, more water rushing in at the valved openings 7 and displacing the air as before. In arranging means for automatically opening and closing the inlet pipe 12, the exhaust pipe 16 leads through and permanently communicates with a pressure chamber 18, one wall of which is a yieldable diaphragm 19. The cast-metal body 20 of the chamber 18 has a 70 depending portion 21 comprising a front part 21^b integral therewith and a rear part 21^c which faces said front portion on a plane parallel with the diaphragm 19, these parts 21^b and 21^c being interposed by a 75 yieldable diaphragm 22 and clamped thereagainst by screw bolts 23. The rear part 21^c is provided with two ports 24 and 25 whose inner ends face the diaphragm 22, the upper portion of the inlet pipe 12 leading into the 80 upper port 24 while the lower portion of said pipe leads from the lower port 25 to the casing 6. A plunger 26 is fitted slidably in the front part 21^b and adapted to be forced rearward to seat the diaphragm 22 in closing 85 contact with the port 24 to close the inlet pipe 12, this plunger being held normally forward away from said diaphragm by an embracing helical spring 27. A pressure-receiving plate 28 is arranged to be acted 90 upon by the diaphragm 19 and is pivoted to lugs 29 on the depending portion 21, the pivotal portion of this plate having a depending integral finger 30 to act on the plunger 26.

In further arrangement, an arm 31 carrying a gasket valve 32 is pivoted to a depending lug 33 on the top 34 of the casing 6 and arranged to seat said valve in closing contact with the inner end of the exhaust pipe 16 in said casing, the free end of this arm having pivoted to it a vertical rod 35 upon which a float 36 is arranged to slide. The lower end of the rod 35 is kept in vertical line by an arm 37 which is pivoted to a lug 38 on the bottom of the casing 6, and the pivotal end of this arm is provided with a weighted arm 39 adapted to rest at full throw on either side of a vertical neutral line A—A shown in Fig. 2. When the casing 6 105

begins to fill with water and drive the air up the exhaust pipe 16, the back pressure set up in the chamber 18 by proper adjustment of the valve 17 forces the diaphragm 19 and plate 28 outward, causing the finger 30 to act on the plunger 26 and instantly seat the small diaphragm 22 to close the inlet pipe 12. As the casing 6 fills with water, the float 36 gradually rises until temporarily arrested by a stop 40 on the upper end of the rod 35, and when the further rise of water increases the buoyancy of the float enough to overcome the gravity of the weighted arm 39 the latter is swung to and past the neutral line A—A with decreasing resistance and increasing momentum, bringing all connected parts to the position shown by the dotted representations in Fig. 2 and closing the valve 32 against exhaust of air. With the exhaust pipe 16 closed below the pressure chamber 18 and the diaphragm 19 thereby relieved from back pressure, the spring 27 withdraws the plunger 26 from the small diaphragm 22 and allows air to again enter the casing 6 through the pipe 12 to force the water up the pipe 14. By permanently closing the valve 15 of the delivery pipe 14, the action of all parts of the apparatus is permanently stopped; but by repeatedly opening said valve or leaving it open the air pressure drives out the water and allows the float 36 to descend until temporarily arrested by a stop 41 on the lower end of the rod 35, and when the further and final lowering of the water allows the float to overcome the gravity of the weighted arm 39 the latter is swung back to and past the neutral line with decreasing resistance and increasing momentum and

brings all connected parts to the initial position shown by the full lines in Fig. 2.

In order to avoid excessive pressure in the casing 6, the pipe 12 may be provided with a regulating valve 42 adapted to limit said pressure to a predetermined amount.

An air-compressor 43 may be provided to supply air to the tank 13.

Having thus described the invention, I claim:—

1. In apparatus of the character described, a casing adapted to be submerged in the water supply and having a valved inlet for water, a source of compressed air, a pipe leading from said source to the casing, an exhaust pipe leading from the casing, means for causing back pressure of the exhausting air in said exhaust pipe, and means whereby said back pressure stops the entrance of air from the said source.

2. In apparatus of the character described, a casing adapted to be submerged in the water supply and having an inlet opening provided with a valve, a source of compressed air, a pipe leading from said source to the casing, an exhaust pipe leading from the casing, means whereby the lowering of the water to a predetermined point in the casing opens the exhaust pipe, means for causing back pressure in the exhaust pipe, and means whereby said back pressure stops the entrance of air from the air source to the casing.

Witness my hand this 6 day of June, 1914.

WILLIAM T. CROSLIN.
